Primary Examiner—Susan J. Lucas*Attorney, Agent, or Firm*—Terry M. Gernstein**[57] CLAIM**

The ornamental design for an adjustable and extendable lantern hanger, as shown and described.

DESCRIPTION

FIG. 1 is a front, top and side perspective view of the adjustable and extendable lantern hanger showing my new design;

FIG. 2 is a front elevational view thereof, the rear being a mirror image of the front shown in FIG. 2;

FIG. 3 is a top plan view thereof;

FIG. 4 is a bottom plan view thereof;

FIG. 5 is a side elevational view thereof; and,

FIG. 6 is an opposite side elevational view thereof.

FIG. 1

FIG. 2

FIG. 3

FIG. 4

FIG. 6

FIG. 5
